PICKER AND METHOD OF MAKING SAME

William Gillet and Edwin L. Morris, Worcester, Mass., and David A. Ahlstrand, Atlanta, Ga., assignors to Graton & Knight Company, Worcester, Mass., a corporation of Massachusetts

Application May 27, 1941, Serial No. 395,344

1 Claim. (Cl. 139—159)

Our present invention is an improved picker, and a method of making same, such picker being for use on a picker stick in a loom. The picker is engaged by the point of the shuttle and is the contacting means for throwing the shuttle across the loom and for receiving the shuttle as it is returned. Such pickers thus involve a high degree of wear and strain as the entire operation of applying power thru the picker stick to throw the shuttle and to receive the shuttle after its passage across the loom is taken up by the picker.

Formerly such pickers were made of leather, rubber, or the like, as constituting a wear-resisting and shock-absorbing material, which will thus stand up under the severe wear involved, and which wear is especially heavy in the present modern high-speed looms.

Our invention is directed to improve and perfect pickers, and more particularly to provide a balanced construction which will insure even wear, uniform action, and longer life. For this purpose, we have improved the type of picker illustrated in U. S. Patent No. 1,904,316, dated April 18, 1933, wherein a leather picker is provided with a pre-formed or pre-molded central recess to engage the end portion of the shuttle back of the shuttle point, thus transmitting all strains and blows from the shuttle thru the picker on a conical surface of substantial area.

A serious difficulty with the construction of prior pickers was that the loop constituting the picker stick-engaging portion was eccentric relatively with the face of the picker, which latter contacted the shuttle. Therefore, the strains, stresses, and consequent wear would work unevenly thru the mass of the picker as the shuttle-engaging point, with the constant hammering incident to use, would tend to work in a non-symmetrical manner, and the picker would be quickly worn out. Furthermore, such unevenness between the shuttle-engaging face of the picker and the stick-engaging loop of the picker resulted in a distortion or twisting, which still further caused the picker to wear unevenly and, hence, was unsatisfactory.

A further difficulty with such prior pickers of the type of said patent, or of other leather pickers wherein the shuttle formed its own recess thru use, was that the wear caused by the constant hammering and blows imparted to and thru the picker would distort the recess and thus throw the entire contact between the picker and shuttle in an eccentric position, thereby quickly destroying the efficiency of the picker.

This difficulty resulted largely because of the fact that the shuttle-receiving recess in the picker had to be positioned as near the bottom of the shuttle box on which the shuttle would

rest and slide and, hence, near the lower part of the picker itself, and, furthermore, because of the constant variation in the density of leather.

5 Our present invention obviates the difficulties above briefly outlined and results in a balanced construction, insuring more even wear, providing for alignment between the shuttle-receiving portion or recess in the face of the picker and the stick-engaging portion, thus preventing twisting, uneven wear, and insuring longer life and usefulness in the picker of our improved construction made by our novel process.

We accomplish these desirable results by a 15 novel and simple method of manufacturing the picker, of yielding material, preferably leather, and in the form of a strip, or strips, for the outer part and a plurality of filler strips, assembling the same in a suitable form with cement or adhesive to unite the layers; and thereupon 20 subject the picker to a molding operation which will aid in consolidating and aligning the mass of the picker in which the shuttle-receiving recess is formed with the stick-engaging loop or portion; and, furthermore, forming the face by 25 beveling, compressing, or the like so as to present a symmetrical, even, and balanced structure.

Furthermore, we prefer to utilize a plurality 30 of thicknesses for the outer portion of the picker, which may be thus formed of two or more strips, or with one strip wound two or more times around the filler members and the form on which the same are assembled. When a plurality of such layers are thus utilized, we also prefer to bevel the lower edges so that when 35 positioning the picker on the picker stick, the fitting may be facilitated, and as the picker is driven onto the picker stick, which latter is also wedge-shaped at the top, the plurality of layers around the loop will not be separated.

Referring to the drawing illustrating a preferred embodiment of our invention and the method of making same:

Fig. 1 is a side view illustrating in diagrammatic form our improved picker on a picker stick and illustrative partially of the path of movement of the picker and stick in association with a portion of the shuttle;

Fig. 2 is an enlarged plan view of our improved picker made in accordance with our present method;

Fig. 3 is a front view of the picker on the same scale as Fig. 2;

Fig. 4 is a cross-sectional view on the line 4—4 of Fig. 3, and

Fig. 5 is a cross-sectional view on the line 5—5 of Fig. 3.

As shown in the drawing, 1 indicates the upper portion of a picker stick on which is fitted

our improved picker designated at 2; and in dotted lines is shown at 3 the end portion of a shuttle which is thrown across the loom by the action of the picker stick, and is received on the opposite side by a picker or other device in the usual standard and well-known type of loom. 4 designates the bottom line of the shuttle box on which the shuttle 3 rests and travels at either end of its reciprocating movement.

The picker of our present invention may be made of any suitable yielding material, such as leather, plastic, rubber compound, or the like but, preferably, is made from a plurality of leather strips or layers and will, accordingly, be so described.

As shown in Figs. 2 and 5, we utilize a leather strip 10 of sufficient length to constitute the outer and encircling portion of the entire picker stick, preferably having a plurality of thickness there-around, including the loop portion of the picker which engages the picker stick. A plurality of inner strips or layers 12, 14, and 16 are assembled, by cement or otherwise, and thereupon the strip 10 is wound about said filler strips 12, 14, and 16 and a form starting at 18 (see Figs. 2 and 5) being bent around the outer end of the filler pieces, as shown at 19, and then along the side 20 around the opposite picker stick form, as indicated at 21, and then along the side 22 across the front portion 23 (see Fig. 5) and then on the outer surface, as indicated at 24, 25, 26, 27, and 28, ending in a bevelled portion at 30 to give a smooth finish and an extra doubled thickness across the main or body portion of the picker. Thereupon, rivets 33 and 35 are applied substantially as shown, and thereafter the front or striking face of the picker is bevelled, as shown at 40 and 41, to form a symmetrical face portion 50, in which we pre-form the shuttle-receiving recess, as indicated at 55, in a symmetrical and balanced position relatively with the face portion 50, which face portion 50 is somewhat eccentric relatively with the main mass or body portion of the picker.

If desired, the shuttle-receiving recess 55 can, of course, be formed first and then the bevelled faces 40 and 41 formed to insure the recess being in proper and balanced relation with the face of the picker, which will insure an even wearing between the shuttle and picker recess and eliminate largely, if not entirely, the normal tendency in the picker to distort the location of such a recess during the continuous hammering and blows incident to use.

With the form removed, a picker stick-engag-

ing opening 60 is left in the picker and the entire plurality of layers being firmly united, preferably by cement and pressure, as well as by the rivets, constitutes a wear-resisting and long-lasting picker with the balanced construction of our invention as described.

The bevelling of the surfaces at 40 and 41 are further important besides insuring a predetermined symmetrical face for the shuttle-receiving recess since these also permit longer layers 12, 14, and 16 to be utilized and, hence, a greater mass of material in the body portion of the picker without interfering with the arc of travel of the picker during reciprocating travel of the shuttle and picker stick. Also, by having the stick-receiving loop and the shuttle-receiving recess in alignment and in balanced relation, our improved picker can be utilized interchangeably either for "rights" or "lefts," and hence this advantage eliminates the necessity heretofore required of having two sets of pickers, one for "rights" and one for "lefts," which formerly involved keeping such two sets in stock, and the expense incident thereto.

25. We claim:

The improved method of manufacturing leather pickers of the kind described, interchangeable for either "rights" or "lefts," which consists in assembling a plurality of filler layers of leather 30 side by side in association with a form simulating a picker stick, thereupon winding about the filler strips and the form an enclosing layer of adhesively coated leather to constitute a plurality of layers secured together by adhesive both across 35 the face of the filler and around the form with the face and loop portions relatively disaligned, thereupon molding the picker, compressing the leather before the adhesive has set of both said 40 filler and enclosing strips into centralized balanced alignment with the loop around the picker stick form, thereupon trimming the face of the picker at both top and bottom to constitute a further balanced relationship of said face with said loop, and thereupon pre-forming a shuttle- 45 receiving recess centrally of the trimmed and compressed head, whereby said recess in the face will be accurately aligned with the center of the picker stick loop, with an equal mass of wearing material above and below the recess, and an 50 equal mass of material on each side of the recess is provided.
